(21) Appl. No.: **29/374,522**(57) **CLAIM**

The ornamental design for a multi-tool with artificial key and LED, as shown and described.

(22) Filed: **Aug. 25, 2011****DESCRIPTION**(51) **LOC (9) Cl.** **03-01**

FIG. 1 is a perspective front view of the multi-tool with artificial key and LED taken from an elevation at the front of the device;

(52) **U.S. Cl.** **D3/210**

FIG. 2 is a perspective rear view of the multi-tool with artificial key and LED taken from an elevation at the rear of the device;

(58) **Field of Classification Search** D11/1-2,

FIG. 3 is a side view of the multi-tool with artificial key and LED;

D11/14, 26-29, 89-92, 44, 48, 81, 99; 63/26-28,

FIG. 4 is a front plan view of the multi-tool with artificial key and LED;

63/32; D3/207-212; D8/38; 70/456 B;

FIG. 5 is a top plan view of the multi-tool with artificial key and LED;

206/37.1; D13/168

FIG. 6 is a rear plan view of the multi-tool with artificial key and LED;

See application file for complete search history.

FIG. 7 is a bottom plan view of the multi-tool with artificial key and LED;

(56) **References Cited**

FIG. 8 is a side plan view of the multi-tool with artificial key and LED taken from the opposite side from that taken in FIG.

U.S. PATENT DOCUMENTS

3; and,

FIG. 9 is a front perspective view of the multi-tool with artificial key and LED with a knife incorporated therein in an open position and shown in phantom.
